UNITED STATES PATENT OFFICE.

WESLEY A. J. HODO, OF CLEBURNE, TEXAS, ASSIGNOR, BY MESNE ASSIGNMENTS, OF ONE-HALF TO H. E. SESSIONS, OF COLUMBIA, SOUTH CAROLINA.

COTTON-GIN OR LINTING-MACHINE

1,286,319.

Specification of Letters Patent. Patented Dec. 3, 1918.

Original application filed April 18, 1916, Serial No. 91,862. Divided and this application filed October 26, 1916. Serial No. 127,889.

To all whom it may concern:

Be it known that I, WESLEY A. J. Hodo, a citizen of the United States, residing at Cleburne, in the county of Johnson and State of Texas, have invented certain new and useful Improvements in Cotton-Gins or Linting-Machines, of which the following is a specification.

My invention relates to cotton gins or linting machines and the object of the same is to provide means for removing lint cotton from the gin saw teeth in a positive and practical and highly efficient manner, and to provide efficient means for taking care of the cotton after it leaves the saw teeth. One difficulty in cotton gins of the character herein set forth has been to take care of the cotton in an efficient manner after it leaves the saw teeth. I have provided practical means for condensing the cotton for the press without running the cotton through the suction fan. This will prevent beating or hammering the lint cotton by the fan blades and will leave the draft clean after it passes through the condenser for other purposes. With such arrangement the draft after it has picked the cotton from the saw teeth and has gone through the condenser and through the suction fan can be utilized for delivering the seed from the gin stands to the seed house.

Another object of the invention is to provide a practical condenser for use in cotton oil mills for taking care of the lint and fine fiber that comes from the gin stands. Heretofore the cotton or linters from each gin stand had to be gathered by men and then delivered to a condenser or press. This operation has been so stifling and dusty that it was difficult to secure help for doing such work and the men had to be switched or laid off frequently because they could not endure the dust. With the arrangements herein described one condenser will answer for a number of gins or linter stands because all of the floating fine fiber will find its way to the condenser and the help heretofore needed for gathering the linters can be dispensed with. This invention is set forth in my application filed April 18, 1916, for cotton ginning, cleaning and bleaching mechanism, which resulted in patent issued November 7th, 1916, No. 1,203,739.

Other objects and advantages will be fully explained in the following description and the invention will be more particularly pointed out in the same. 55

Reference is had to the accompanying drawings which form part of this invention.

Figure 1 is a diagrammatic view partly 60 in section illustrating the improvements herein set forth.

Fig. 2 is a longitudinal section of the condenser.

Fig. 3 is a broken section of the same 65 illustrating the driving gear.

Fig. 4 is a detailed view of the driving gear.

Similar characters of reference are used to indicate the same parts throughout the 70 several views.

The drawings show parts of the gin stand provided with a shaft 1 and a gang of saws 2 with the usual ribs 3. The cotton is stripped from the saw teeth by a draft 13, which is provided with a nozzle 4 terminating close to the saw teeth. The flue has a horizontal portion 7 connected with the nozzle 4 and an inclined portion 6 connected with the flue, forming an offset at 8 with the nozzle 4. This construction makes an enlarged portion of the flue 9 for the purposes of cleaning and purifying the cotton, as set forth in said patent. The enlarged 75 portion 9 is provided with a door 10 for removal of trash and with a baffle 11 which cooperates with the enlarged portion for cleaning purposes. A section 12 of a branch flue is shown connected with the flue 13. 80 The details of the flues will not be set forth herein as these elements are fully set forth in said patent. 85

The condenser is of ordinary construction including a frame 14 and a revolving screen drum 15 mounted on a shaft 22 journaled therein. A wind shield 21 is used within the screen drum for controlling the draft and for preventing the draft interfering with the condensing of the cotton. The 95 screen drum revolves in the direction indicated by the arrow and as soon as that part of the screen passes behind the wind shield 21 the cotton is left free to lie flat on the screen drum and pass on around and out 100 between the doffing rollers 17 and 18. The 105

draft passes out through that part of the screen drum which is not protected by the wind shield 21 and then out through the flue 20 through the suction fan 5. The suction fan may be driven by the pulley 45. A section 44 of a nozzle is shown in communication with the fan 5 which is used to discharge a portion of the draft to prevent back pressure through the flue 20. The other part of the draft is discharged through a flue 28 to drive the seed from the seed hopper 29 to the seed house or to some place where the seed may be stored or hauled away. The screen drum may be driven by cog-wheels 25 which are to be made rigid with the shaft 22 and by pinions 26 which mesh with cog-wheels 25 and are driven by shaft 27 which is journaled in an offset in the frame 14.

20 The claims herein are divided from the application above noted.

What I claim is:—

1. In a cotton gin or linter provided with a gang of saws, means for stripping lint from said saws consisting of a suction nozzle, a lint flue into which the nozzle discharges the lint, a condenser connected directly to the said lint flue, and a fan for creating a suction current through said condenser, lint flue and nozzle, said condenser being located, as to the suction current, between said lint flue and the fan, said suction nozzle and suction current constituting the only means for stripping lint from said gang of saws, said fan discharging said current from the ginning operation when the current passes through the fan.
2. In a cotton gin or linter provided with a gang of saws, means for stripping lint from said saws consisting of a suction nozzle commencing in close proximity to said gang of saws and leading therefrom, a lint flue into which said nozzle discharges the lint, a condenser connected directly to the said lint flue, and a fan for creating a suction current through said condenser, lint flue and nozzle, said condenser being located, as to the suction current, between said lint flue and the fan, said suction nozzle and suction current constituting the only means for stripping lint from said gang of saws, said fan discharging said current from the ginning operation when the current passes through the fan.
3. In a cotton gin provided with a gang of saws, means for stripping the lint cotton from the saw teeth and for condensing the cotton consisting of a nozzle commencing in close proximity to the saw teeth, a flue connected to said nozzle, a suction fan, a revolving screen drum between the nozzle and said fan, and a flue connected to the discharge of said fan for driving the seed from the gin stand.

only means for stripping the lint from said gang of saws.

2. In a cotton gin or linter provided with a gang of saws, means for stripping lint from said saws consisting of a suction nozzle commencing in close proximity to said gang of saws and leading therefrom, a lint flue into which said nozzle discharges the lint, a condenser connected directly to the said lint flue, and a fan for creating a suction current through said condenser, lint flue and nozzle, said condenser being located, as to the suction current, between said lint flue and the fan, said suction nozzle and suction current constituting the only means for stripping lint from said gang of saws, said fan discharging said current from the ginning operation when the current passes through the fan.

3. In a cotton gin provided with a gang of saws, means for stripping the lint cotton from the saw teeth and for condensing the cotton consisting of a nozzle commencing in close proximity to the saw teeth, a flue connected to said nozzle, a suction fan, a revolving screen drum between the nozzle and said fan, and a flue connected to the discharge of said fan for driving the seed from the gin stand.

In testimony whereof, I set my hand,
this 21st day of October, 1916.

WESLEY A. J. HODO.
